UNITED STATES PATENT OFFICE

167,400

OUTDOOR FLOWER BASKET

Elwyn M. Gipson, Lufkin, Tex.

Application April 2, 1952, Serial No. 19,171

Term of patent 14 years

(CL. D35—3)

To all whom it may concern:

Be it known that I, Elwyn M. Gipson, a citizen of the United States and a resident of Lufkin, county of Angelina and State of Texas, have invented a new, original, and ornamental Design for an Outdoor Flower Basket, of which the following is a specification, reference being had to the accompanying drawing, forming a part thereof.

Fig. 1 is a side elevational view of an outdoor flower basket, showing my new design;

Fig. 2 is a top plan view;

Fig. 3 is an end elevational view; and

Fig. 4 is a bottom plan view thereof.

The side of the design not shown presents the same appearance as the side shown in Fig. 1.

I claim:

The ornamental design for a outdoor flower basket, as shown and described.

ELWYN M. GIPSON.
